UNITED STATES PATENT OFFICE.

VAN B. NEAL, OF DESOTO, OHIO.

CALCULATING DEVICE.

No. 838,132.

Specification of Letters Patent.

Patented Dec. 11, 1906.

Application filed December 15, 1905. Serial No. 291,830.

To all whom it may concern:

Be it known that I, VAN B. NEAL, a citizen of the United States, residing at Desoto, in the county of Brown and State of Ohio, have 5 invented certain new and useful Improvements in Calculating Devices, of which the following is a specification.

My invention contemplates means whereby a storekeeper may calculate without the 10 necessity of arithmetical computations the price of any measured amount of vendable commodities sold. For instance, it is well known that under the present general practice if a storekeeper sells a certain number 15 of pounds of goods, dozens or other numbers of articles, yards or other linear measures of dry goods or the like, or gallons of liquids it is necessary for him to figure with his pencil and pad the selling price of the quantity 20 or amount sold on a basis of one yard, one dozen, &c.

The object of my invention is to do away 25 with the necessity of this computation and provide an improved and simple calculating device embodying calculating-disks containing by predetermined calculations the selling price of various amounts, the said disks co-acting with price-plates on a support so arranged that by turning the disks on the support or turning the support with respect to 30 the disks until the quantity sold arrives at a predetermined point a pointer will indicate the price of the individual amount and the aggregate selling price of the quantity disposed of. The disks are to be interchangeable, and there are to be as many of them as 35 may be desired, according to the character of the business employing the invention and the diversified character of the goods sold.

40 For a full description of the invention and the merits thereof and also to acquire a knowledge of the details of construction of the means for effecting the result reference is to be had to the following description and 45 accompanying drawings, in which—

Figure 1 is a face view of one embodiment of my invention. Fig. 2 is a vertical longitudinal sectional view on the line $x-x$ of Fig. 1. Fig. 3 is a horizontal section on the line 50 $y-y$ of Fig. 1.

Corresponding and like parts are referred to in the following description and indicated in all the views of the drawings by the same reference characters.

55 Referring to the drawings, the numeral 1 designates a support which is provided with

a front-edge slot 2 and a side-opening slot 3 and a longitudinally-extending guideway or slot 4. Entered in the edge-opening slot 2 is any desired number of revoluble disks 5, 60 which are mounted to rotate about their centers on shafts 5^a, each of which is provided with a clamping-nut 5^b, by which the disk may be turned the required distance. The shafts 5^a are preferably located in recesses or 65 guideway portions 6 in one edge of the side-opening slot 3. It is to be understood that the shafts 5^a of the disks may be connected to any desired form of measuring device and so arranged that the calculations on the disks will 70 indicate by the positions of the disks the quantity passed through said measuring device. In the present instance, however, the disks are turned by their clamping-nuts 5^b and secured in proper position. 75

Along one edge of the side-opening slot 3 there is secured to the support a number of price-plates 7, according to the number of disks mounted at one time upon the support. These price-plates 7 are each provided at 80 both ends with a longitudinal slot 7^a, in which set-screws 7^b are mounted to adjustably and detachably secure the said plates to the support so that the plates may be changed whenever desired, according to the particular 85 disks employed therewith, and may also be longitudinally adjusted whenever desired. These price-plates 7 are provided along one edge with suitable indicia, such as numerals determining the price per dozen, price per 90 yard, price per gallon, or price per pound, according to the disks employed and according to the commodity the aggregate price of which it is desired to determine.

8 indicates pointers. There are two of these 95 pointers for each disk 5, and each pair of pointers are secured together and are adjustably mounted by a set-screw or similar device 8^a, working in the slit or guideway 4. Each pointer 8 is provided with two heads, the fingers 8^b of which are preferably rigidly secured together and are preferably colored differently, so as to have a contrasted appearance, so that they may be readily distinguished. One of the fingers points directly inward and 100 toward the edge of the side opening 3, and said finger is designed by the position of the pointer in the guideway 4 to point to any one of the selling prices contained on the price-plate 7, with which it is designed to coat. 105 The other finger is angular in formation and preferably has its extremity pointing down- 110

wardly over the edge of the side-opening slot 3 beyond the price-plate 7 and is designed to point to the various amounts on the revoluble disks 5 as said amounts arrive in juxtaposition to the number on the price-plate pointed to by the first-named finger.

The disks 5 are provided, preferably, on their rims with a circumferentially-extending series of numbers indicating the different quantities of goods—as, for instance, "1 2 3 4" &c.—referring to either pounds, yards, gallons, or the like or dozens or single articles. The said disks also contain within their margins a plurality of numbers arrived at by predetermined calculations of the various prices of the articles and the various quantities to be sold.

In the practical operation of the device I will for the purpose of description give a simple illustration of how the device works. Let it be assumed that it is desired to compute the selling price of a quantity of eggs. If eggs are selling at the time at twenty-five cents the dozen and four dozen are sold, the disks 5 will be turned until the numeral "4" shows beyond the edge of the side-opening slot 3, which will indicate that four dozen have been sold, and the pointer 8 will be arranged with its price-finger pointing to the numeral "25" on the price-plate 7. Then the upper finger of the pointer will, as is manifest, point to "\$1.00" on the disk 5, which without further calculation will tell the storekeeper what the aggregate selling price amounts to. I might give other more complicated examples of the use of my device, but deem that the foregoing is sufficiently clear to show the operation under different circumstances.

While I have here shown two disks and their related parts, it is evident that one or any other number of disks and pointers and the like may be employed within the scope of my invention.

Having thus described the invention, what is claimed as new is—

1. A device of the character described, comprising a support provided with an edge-opening slot and a side-opening slot communicating therewith and also provided with a longitudinal guideway adjacent said side-opening slot, and revoluble calculating-disks entered in said edge slot and mounted to turn with its face showing through said side-opening slot and said face containing calculations, a price-plate detachably and adjustably secured adjacent one edge of said side-opening slot and containing figures denoting the different selling prices of commodities by the pound, or gallon or the like, and a pointer adjustably mounted in said guideway and

provided with two fingers designed to point respectively to a number on the price-plate and a predetermined number on said disk.

2. A device of the character described comprising a support, and revoluble disks mounted on said support and provided with calculations on one face, the support being provided with a guideway, a price-plate secured to said support and a pointer mounted in said guideway and provided with two fingers one of which is designed to point to said price-plate and the other to the calculations on said disks.

3. A device of the character described comprising a support having an edge-opening slot and a side-opening slot and a guideway adjacent the latter, and calculating-disks entered in said edge-opening slot with one face appearing through the side-opening slot and revolvably mounted in said support, means for turning said disk to hold it in different adjusted positions, a price-plate provided at each end with a longitudinal slot and a set-screw working through said slot into said support whereby the price-plate may be adjustably and detachably connected to the support, and a pointer provided with a set-screw working in said guideway and provided with two fingers one of which is designed to point to different numbers on the price-plate and the other of which is designed to point to calculations on the disk.

4. In a device of the character described the combination of a series of interchangeable disks and a series of interchangeable price-plates for each of said disks, and a two-fingered pointer designed to point to the price-plates and said disks.

5. In a device of the character described the combination of a support, a series of interchangeable disks designed to be revolvably mounted on said support and each provided with calculations for articles sold by either the pound, dozen, yard, or gallon or the like, a series of interchangeable price-plates designed to be detachably secured to said support and there being one price-plate for each disk, the said price-plates containing numbers indicating the different prices per dozen or per yard or the like according to the disk employed therewith, and a two-fingered pointer adjustably mounted on said support and designed to point respectively to the numbers on said price-plate and to the calculations on the disks.

In testimony whereof I affix my signature in presence of two witnesses.
